RALPH WESLEY STEWART, OF CLIFTON CITY, MISSOURI

TRAIN ORDER HOLDING MEANS

Application filed September 21, 1931. Serial No. 563,923.

My invention relates to means for properly holding the usual train order hoops in place adjacent to the right-of-way and in proper vertical spaced relation so that the engine-
men, namely the engineer and the firemen, as
well as the trainmen may each receive his
copy or copies of the train order or orders;
each order being held by a separate hoop so
positioned on a staff that it may be readily
grasped or received by the enginemen and
trainmen while the train is passing the loca-
tion of said means.

The purpose of my invention is to provide
means which will eliminate the need for an
attendant or stationman to stand along the
right-of-way while attempting to deliver the
orders to the train crew while the train is in
rapid motion.

The object of my invention is to provide
means of the character defined which will
maintain the respective order holding hoops
in proper position against vibration or the
action of wind while at the same time yield-
ingly holding the hoops so they may move in
the general direction of the passing train
while the members of the train crew are
grasping the different order holding hoops
intended for the respective members of the
crew.

The objects and advantages of my invention
will be more readily comprehended from
the detailed description of the accompanying
drawing, wherein—

Figure 1 is an elevation of my improved
means illustrating a train order hoop in position.

Figure 2 is a perspective view of a portion
of the means provided with a train order
holding hoop of which the hoop portion is
broken away.

Figure 3 is a partial side and sectional view
of the portion shown in Figure 2 as viewed
from the opposite side.

Figure 4 is a side elevation as viewed from
the order holder receiving side, with portions
broken away to show the holder receiving
socket.

My invention relates to suitable means for
receiving and holding the usual train order
holding hoops and obviating the necessity for

an operator or attendant to stand close to
passing trains while holding up the various
hoops at suitable elevations where they can
be grasped by the train crew while the train
is moving past the order delivering station. 55

Heretofore train orders or messages have
been delivered to passing trains by an attend-
ant holding the order holders in which the
orders are secured; one end of each holder be-
ing in the form of a hoop through which the
arm of the member of the train crew may be
slipped while the train is passing, which is
often at high speed. This method is not en-
tirely dependable because the attendant fre-
quently fails to release his hold at the proper
instant or fails to hold the hoop-end of the
holder in proper position where it can be re-
ceived by the intended member of the train
crew.

Furthermore, this method often necessi-
tates members of the crew leaving their
proper positions or seats in order that they
may grasp the hoop intended for them and
hence detracting the enginemen's attention
from the track ahead. 75

Furthermore, this method has frequently
resulted in injury to the attendant by reason
of falling coal from the tender, swinging car
doors, overhanging wires whereby shipments
may be fastened on gondola or on freight cars
or from flying ballast; and has also resulted
in an engineman slipping on the deck of the
tender or on the steps in his effort to receive
the order holder intended for him by the per-
son holding the order holding hoops. 80

My improved means is intended to elimi-
nate these serious objections and to provide
means which will properly hold the train
order holding hoops in proper position and in
its specific embodiment involves a tubular
staff or pipe 10 of proper height in order that
the respective train order holding hoops, one
of which is indicated at 11, may be posi-
tioned at different heights in keeping with the
positions of the different members of the crew
so that each may receive his copy of the order
or orders as the train is passing the point
where the staff is located. For example, the
tubular staff 10 may be eleven feet in height
and secured in a suitable foundation as at 12 95
100

so it may be maintained in fixed vertical position arranged at a predetermined point along the right-of-way and in proper proximity to the track. This staff 10 is shown consisting of a suitable pipe of proper diameter and strength, with the lower portion above the supporting base provided with suitable foot-holds or step brackets 13 arranged on opposite sides and at suitable distances apart vertically in order that an attendant may climb up the staff to place the order holding hoops in their respective sockets.

The staff, at suitable predetermined distances apart vertically and on the same side thereof, is provided with transverse openings or slots 14 more clearly shown in Figures 1 and 2. At a suitable distance beneath each slot 14, the interior of the staff or pipe 10 is provided with a stop member or block 15 held in position in any suitable manner, as for example by a transverse rivet or bolt as at 16. The slots 14 are preferably two and a half inches wide and about five inches long to permit the loop handle to work freely up and down without binding.

Rotatably mounted in the staff or pipe and resting on the stop block 15 is a cylindrical block 17 of suitable length with its upper end exposed at its respective opening or slot 14; the blocks 17 being preferably of more or less length so as to prevent any binding effect. That is to say, the blocks 17 should be free to rotate in the staff or pipe 10. The top of each rotatable block 17 (a similar block being mounted at each slot 14) is provided with a square or preferably angular groove 18, see Figure 4, for the purpose of receiving the preferably square handle portion 19 of the train order holding hoop 11.

Slidably mounted in the staff or pipe 10 immediately above the hoop holding member 17 is a weight block or element 20 adapted to rest on the block 17 and therefore also on top of the handle 19 in the squared groove 18 of block 17, thereby maintaining the hoop in proper horizontal position, as shown in Figure 1.

My improved staff, as disclosed in the drawing, is shown provided with three order holding or hoop receiving slots 14 and therefore it will be understood that the staff or pipe 10, adjacent to each slot 14, is provided with a stop block 15, a rotatable block or element 17 and a weight block 20.

It is apparent from the construction shown that the holding blocks 17 with the order holding hoops are free to swing and rotate in a horizontal direction thereby enabling the handles 19 of the hoops to be readily withdrawn from the angular or squared grooves 18 while the train is in motion because the blocks or elements 17 will rotate in the direction of train travel and dispose the squared groove 18 in the general direction of the moving train, which enables the order holding

hoop to slide out longitudinally from the groove.

In order that the order holding hoops may be in proper position, namely in a direction disposed toward the track and be held against vibration or the action of wind, I provide yielding means for maintaining the initial positions of the hoops, namely the position shown in Figure 1. This means has been shown in the form of the parallelly arranged spring fingers 21. These fingers 21, in the particular exemplification, are shown consisting of a strip of resilient metal bent to provide the two depending fingers 21 which are intended to engage with opposite sides of the squared or angular portion or handle 19 of the order-holding hoop 11. The bowed portion of the resilient strip is shown bent about a suitable pin 22 secured in the side of the staff or pipe 10 at a suitable distance above each transverse slot 14; the finger strip being clamped in place by a suitable pin or bolt as at 23; or may be welded on pin 22. The pin 22 and the spring fingers are rigidly secured in place at a suitable distance, for example say six inches above each slot 14.

The train order holding hoop is inserted into its respective groove in the rotative block 17 with the fingers 21 spread apart so as to engage opposite sides of the handle 19, as shown in Figures 1 and 2. It is apparent that a horizontal movement or swinging of the hoop through the action of wind or vibration is impossible, while on the other hand the fingers 21 will flex sufficiently when the hoop is grasped by the engine crew to allow the fingers to snap across the handle and permit the handle 19 to free itself from member 17.

In order that the openings in the staff may be closed against the ingress of snow and rain when not in use, I provide the staff with slideable closure members 24. The closure members 24 each consist of an arcuate or semi-cylindrical metal plate slidably held in place by the flanged rings 25, 25 arranged above and below each slot 14, see Figure 3; and the slide plates or closure members 24 are each provided with a suitable hand grasp as at 26 which enables the closure member to be rotated about the staff so as to cover the slot 14 when the staff is not in use and thus prevent the ingress of snow and the like through the slot 14.

The flanged rings 25, and especially the lower ring of each pair, may be provided with suitable holes or openings as at 25^a to permit rain, snow or ice to drain out of the slideway for the closure members 24.

The upper end of the staff is also preferably provided with a hand grasp and lantern-holding bracket, as at 27; while the top of the staff or pipe is preferably provided with a suitable cap, as at 28, Figure 1, which may be

formed to receive a road indicating plate as at 29.

The order holding hoop 11 may be substantially similar to the hoops at present employed, being preferably provided with a handle 19, either angular or square in cross-section in order that it may not rotate in the groove 18 and so that the fingers 21 may have effective holding relation therewith as heretofore described. The inner end of the staff or handle 19 is provided with a slit as at 30, Figure 1, in which the orders are placed; while the ring or hoop portion 31 is of sufficient size to permit it to readily slip onto the extended arm of a member of the train crew while the train is in motion. These holders, after the order or orders have been removed by the trainmen, are then thrown out along the right-of-way to be gathered up by the station attendant for subsequent use.

I have shown what I believe to be a simple embodiment of the invention which has been described in terms employed merely for purposes of description and not as terms of limitation, as modifications may be made without, however, departing from the spirit of my invention.

What I claim is:

1. Train order holding means comprising, in combination with train order holding hoops having elongated handles; a vertical standard provided with transverse slots at prearranged vertically spaced points; means mounted in the standard at each slot so as to rotate transversely of the standard in directions lengthwise of the slots and adapted to receive one end of a train order holder; and yielding means whereby accidental rotation of the first means is prevented and the position of the order holder is maintained.

2. Train order holding means comprising a tubular standard provided with transverse slots at predetermined vertically spaced points; a socketed member rotatably mounted in the standard coincident with each slot adapted to receive one end of a train order holder; and yielding means secured to the standard adjacent to the slots adapted to maintain the order holders in prearranged positions.

3. Train order holding means comprising a tubular standard provided with transverse slots at predetermined vertically spaced points; a grooved block rotatably mounted in the standard coincident with each slot adapted to receive one end of a train order holder; yielding means secured to the standard adjacent to each slot for maintaining the position of the order holder; and closure means for said slots.

4. Train order holding means comprising, in combination with an order holding hoop member provided with a handle rectangular in cross-section; a tubular standard provided with a transverse slot; a block rotatably

mounted in the standard coincident with the slot and provided with an angular groove in its upper face adapted to receive the handle of the order holding hoop; means yieldably mounted in the standard on the block for holding the hoop in horizontal position; and spring fingers secured to the standard and adapted to engage opposite sides of the order holder handle for normally maintaining the holder in prearranged position.

5. Train order holding means comprising a vertical tubular standard provided with transverse slots at predetermined vertically spaced points; an order holder receiving member in said standard coincident with each slot and arranged to move horizontally; a closure member for each slot slidably mounted on the standard; and yielding means for holding the order holders against accidental lateral movement.

6. Train order holding means comprising a vertical tubular standard provided with transverse slots spaced apart vertically and with lantern holding means; a grooved block rotatably mounted in the standard coincident with each slot; a weight member loosely mounted in the standard above each grooved block adapted to cooperate with the groove for loosely holding a train order holder in horizontal position; a closure member for each slot slidably mounted on the standard; and spring fingers arranged adjacent to each slot for yieldingly holding the order holders against accidental lateral movement.

7. Means of the character described comprising, in combination with train order holding hoops having elongated handles; a hollow vertical standard provided with transverse slots at predetermined vertically spaced points; a socketed member, rotatably mounted in the standard coincident with each slot, adapted to receive one end of the handle of an order holding hoop; and yieldable means in the standard above each socketed member and cooperating therewith to hold the order holder in horizontal position.
